UNITED STATES PATENT OFFICE

ANDRÉ MELIN, OF PARIS, FRANCE

DESIGN FOR A BOX COVERING

Application filed July 9, 1932. Serial No. 44,288. Term of patent 14 years.

To all whom it may concern:

Be it known that I, ANDRÉ MELIN, a citizen of the Republic of France, residing at 30, Quai du Louvre, Paris, France, have invented a new, original, and ornamental Design for Box Covering, of which the following is a specification, reference being had to the accompanying drawing, forming part thereof.

The figure is a plan view of a box covering, showing my new design.

I claim:

The ornamental design for a box covering, as shown.

Dated May 27, 1932.

ANDRÉ MELIN.
